UNITED STATES PATENT OFFICE.

ASMUNDUR LOPTSON AND GEORGE HENRY RICHARDSON, OF BREDENBURY,
SASKATCHEWAN, CANADA.

GRAIN-STOOKER.

1,246,963.

Specification of Letters Patent. Patented Nov. 20, 1917.

Application filed May 15, 1916. Serial No. 97,715.

To all whom it may concern:

Be it known that we, ASMUNDUR LOPTSON and GEORGE HENRY RICHARDSON, both subjects of the King of Great Britain, and 5 residents of the village of Bredenbury, Province of Saskatchewan, Dominion of Canada, have invented certain new and useful Improvements in Grain-Stookers, of which the following is a specification.

10 Our invention relates to improvements in grain stockers, and the principal objects of our invention are first: to design an implement of this class which will have what we may term an overthrow action so that 15 the sheaves comprising the stool may be firmly placed butt end down without any danger of threshing the grain, and after the manner in which a man handles a sheaf, so that the stool will stand up without any 20 manual attention having to be given thereto, and second: to enable the stooking to be carried out at a greater speed than is possible by manual labor, and broadly considered the invention comprises a sheaf holder 25 designed to contain the desired number of sheaves; a suitable frame in which the sheaf holder is mounted; a binder mounted beyond the forward end of the sheaf holder; retaining means carried by the sheaf holder to retain 30 the sheaves in place when the sheaf holder is being inverted; means for opening said retaining means when the sheaf holder is being filled, and a suitable reversing gear for actuating said sheaf holder, as herein- 35 after particularly set forth.

Figure 1 is a plan view of our implement showing the same mounted adjacent a binder deck. Fig. 2 is an elevation at the rear end of the implement illustrated in Fig. 1 showing in side elevation the operating gear therefor. Fig. 2^a, is a view on an enlarged scale of the operating mechanism at the right of Fig. 2. Fig. 3 is a side elevation of the sheaf holder and the frame therefor, parts being broken away and shown in section. This view also shows a front view of the reversing cam gear wheel for the sheaf holder. Figs. 4 to 9 both inclusive are face views of the reversing cam gear 40 wheel on an enlarged scale. Fig. 10 is a cross section on the line 6—6 Fig. 6. Figs. 11 to 14 both inclusive are views in side elevation of the sheaf chute and operating means therefor. Figs. 15 and 16 are 45 schematic views showing an end elevation

of the parts illustrated in Figs. 11 and 12. Figs. 17 to 20 both inclusive are side views of the sheaf holder showing the different positions of the same, and Fig. 21 is a perspective view of certain operating means for 60 the means for holding the sheaves within the sheaf holder.

In the drawings, like characters of reference indicate corresponding parts in each figure.

Any suitable frame may be provided in which to mount the sheaf holder. We show this frame as composed of horizontal members 2, 3 and 4. The members 2 and 4 are coupled together by the cross member 5. 70 The horizontal member 3 is coupled to the member 4 by the parts 6 and 7. These parts together with members 2 and 3 form a frame in which is journaled the axle 8 of the drive wheel 9. The said axle is also 75 journaled in the uprights 10 which are secured respectively to the horizontal member 2 and the supporting member 11 which is carried by the horizontal member 2. The supporting member 12 corresponding to the 80 supporting member 11 is carried by the horizontal member 4. The supporting members 11 and 12 project above the horizontal members 4 and 2, and journaled in the same are the ends 13 of the axle 14. This axle is 85 secured by any suitable means such as bolts 15 to the sheaf holder 16. By any suitable coupling means 170, the frame of our implement is attached to any suitable portion 180 of the binder (not shown). 90

The sheaf holder 16 may be of any desired shape, though it is preferably shaped like a frustum, and the upper side thereof is removed as shown clearly in Figs. 1 and 2. Of course each end of the sheaf holder 16 95 is open so that the sheaves will project therebeyond as illustrated in Figs. 17 to 20. The smaller end of the sheaf holder 16 is provided with a retaining member 17 hinged thereto by the pintle 18. This retaining 100 member is closed when the sheaf holder 16 is full, and so retains the sheaves in position while the sheaf holder is being manipulated to dump the sheaves on the ground. When the sheaf holder 16 is being filled with 105 sheaves, the retaining member 17 occupies the position illustrated in Figs. 1 and 2. As illustrated particularly in Figs. 1 and 2, the sheaf holder 16 is positioned opposite to and below the binder deck 19. As sheaves are 110

formed they are moved by the usual arms 20 from the binder deck onto the table 21 which is carried by said binder deck. This table is shaped substantially to conform to 5 an arc described by the arms 20 and to the upper end thereof is hinged the sheaf chute 22 by the pintle 23. This sheaf chute normally occupies the position illustrated in Figs. 1 and 2 in full lines, and in order to 10 coöperate with the preferred shape of the sheaf holder, the said sheaf chute tapers toward its front end on one side as shown clearly in Fig. 1. Each sheaf as it escapes from the table 21 passes over the chute 22 15 and onto the sheaf holder 16.

We will suppose that the sheaf holder 16 is full, and therefore the driver in control of the binder desires to dump the same. Any suitable trip mechanism (not shown) 20 preferably designed to be operated by the foot, is pressed, and since the cable or chain 24 is connected therewith, this cable pulls down on the arm 25 pivoted at 26 to one of the uprights 10. The inner end of the arm 25 25 is associated in the usual way with the coupling member 27 feathered on the shaft 28, and as this shaft 28 is continuously rotated during the movement of the implement, when the coupling member 27 is coupled to the gear wheel 29, and as this gear wheel is constantly in mesh with the gear wheel 30 secured to or forming a part of the reversing cam 31, it follows that this reversing cam must be rotated in order to 30 35 rorate the sheaf holder 16, as the said cam 31 is keyed to one end of the axle 14. Pivoted to the outer end of the arm 25 is a rod 32 which passes through the outer end of the lever 33 which is pivoted at 34 to the bracket 40 35 carried by the cross piece 36 which couples the uprights 10 together. Journaled on the inner end of the lever 34 is a roller 37 preferably tapered, and in its normal position this roller occupies the space 38 45 (see Fig. 4) separating the flanges 39 and 40. Immediately the arm 25 is pulled downward as described and the gear wheel 29 ready to operate, the roller 37 has been moved out of the space 38 so as to permit of 50 the rotation of the reversing cam 31. The reversing cam is moved as described, and the roller 37 tracks on the cam face 41 of the flange 40 (see Fig. 5). The reversing cam 31 is moved in the direction indicated 55 by arrow in Figs. 6 and 7. So soon as the space 42 which separates one end of the flange 39 from the flange 40 moves opposite the roller 37, the spring 43 which couples one end of the arm 25 to the cross piece 36 60 exerts pressure, and moves the lever 33 through the medium of the rod 32 and certain other parts carried thereby hereinafter described, so as to cause the roller 37 to pass through the space 42 and track against the 65 cam face 44 of the flange 40 (as shown in

Figs. 8 and 9). Simultaneously the roller 37 is in position to track against said cam face 44, through the medium of the rod 32 and lever 33, the arm 25 is operated to unclutch the gear wheel 29 from the shaft 28 70 and to clutch the gear wheel 43 to said shaft. The result is that the gear wheel 30 is reversed in its direction of rotation so that the sheaf holder 16 will ultimately be brought back to normal position. Of course 75 it will be understood that the operator having once pulled on the cable 24 will release all pressure thereagainst in order to allow for the freedom of movement of the parts before described to effect the reversal of the 80 sheaf holder.

In order to move the roller 37 back into the space 38 immediately the sheaf holder 16 has been returned to normal position, we provide any suitable means such as a switch 85 45 which is secured to the inner side of the flange 39, and which occupies a position between the inner end of the space 38 and the gear wheel 30. The inner end 46 of this switch is shaped substantially as shown in 90 Figs. 4 to 9, and is resilient so that when this switch comes in contact with the roller 37 this switch will force this roller up into the space 38. When this roller occupies this space, the coupling member 27 is moved into 95 the position illustrated in Fig. 2, and therefore the reversing gear for the sheaf holder 16 is brought to rest.

As will be understood the gear wheels 29 and 43 are respectively mounted on sleeves 100 a and b suitably held in place. The shaft 28 has suitable bearing in the cross piece 36 and in the cross piece 47. 48 is a pinion keyed to the lower end of the shaft 28 and constantly in mesh with the gear wheel 49 105 which is keyed to the axle 8 of the wheel 9.

By means hereinafter described, shortly before the sheaf holder 16 is inverted, the retaining member 17 is closed and kept closed during the placing of the stock on the 110 ground.

Figs. 3 and 17 represent the normal position of the sheaf holder 16. In Figs. 18, 19 and 20 the positions of the sheaf holder 16 correspond to the positions of the reversing cam 115 illustrated respectively in Figs. 5, 6 and 7. From Figs. 20 to 17 both inclusive will be understood the reverse movement of the sheaf holder 16 as it is brought back to normal position.

The shape of the sheaf holder 16 of course must be such as to allow for the additional room necessary at the butt end of the sheaves so that when the sheaf holder occupies the position illustrated in Fig. 20 the stock will 125 be deposited on the ground.

The sheaves will be passed from the binder deck 19 during the dumping of the sheaf holder, and we have therefore provided means for temporarily holding a number of 130

- sheaves during dumping of the sheaf holder. Our preferred means for this purpose comprises a frame composed of two side members 50 the inner ends of which are coupled to a sleeve 51 mounted on the rod 52 which carries the arms 20. The side members 50 are preferably coupled together at their outer ends by the cross piece 53. By means hereinafter described, during the dumping of the sheaf holder 16, the sheaf chute 22 is supported in the dotted position illustrated in Fig. 2. As the sheaves are delivered by the arms 20 over the table 21, they are stored between the side members 50 and the sheaf chute 22 as illustrated in this figure. So soon as the holder 16 returns to normal position, the sheaf chute 22 drops down and permits the stored sheaves to pass into said sheaf holder.
- 20 The frame composed of the side members 50 and the cross piece 53 is resiliently mounted so as to yieldingly support the sheaves in coöperation with the sheaf chute 22, and to prevent the sheaves from dropping backward onto the table 21, any suitable catches may be provided. These catches 54 are shaped substantially as shown and are carried by the underside of the side members 50.
- The preferred means for operating the sheaf chute 22 is as follows: Mounted on one of the ends 13 of the axle 14 is a rotary segmental member 55. In its normal position as illustrated in Figs. 2, 11 and 15, the flat edge 56 thereof is resting against the underside of the sheaf chute 22. So soon as the axle 14 is moved to invert the sheaf holder, the segmental member 55 is of course moved into the various positions illustrated in Figs. 11 to 16. As the said segmental member moves it raises up the sheaf chute 22, and when the arc-shaped edge 57 thereof is in contact with said sheaf chute, this sheaf chute is held in the dotted position illustrated in Fig. 2 and in the position illustrated in full lines in Fig. 16.
- We shall now describe the preferred means for opening and closing the retaining member 17. Mounted on the pintle 18 is a sleeve block 58 which is locked to said pintle by a set screw 59. Carried by the sleeve block 58 is a spring rod 60 the free end of which is provided with an eye 61 through which passes the loops 62 carried by the retaining member 17 near the free end thereof. Also keyed on the pintle 18 by a set screw 63 is a sleeve block 64. Secured in this sleeve block is a lever 65 coupled at its outer end to the upper end of the arm 66 carried by the lever 67 loosely mounted on one of the ends 13 adjacent the uprights 10. 68 is an arm keyed as at 69 to one of the said ends 13 of the axle 14. The arm 68 is coupled to the lever 67 by a spring 70 which exerts tension to normally hold the lever 67 in contact with the stop 71 carried by the supporting member 11. As the sheaf holder 16 begins to move, and since the lever 67 is held by the spring 70 in contact with stop 71, the lever 65, in co-action with the arm 66 will move the pintle 18 in the direction indicated by arrow in Fig. 21, and so in due course close the retaining member 17. In due course through the movement of the arm 68, the lug 72 carried thereby comes in contact with the arm 67, thus moving this arm around. When the sheaf holder 16 has reached the position illustrated in Fig. 20, the same starts to return to normal position, and during this movement of the same, the axle 14 of course is moved, and during the return to normal position, the lever 67 comes in contact with the stop 71, thus being arrested in its movement, and during the further movement of the sheaf holder 16 and the arm 68 back to normal position, through the co-action between the lever 65 and arm 66, the retaining member 17 is opened.
- While the spring 70 in the position of the parts illustrated particularly in Fig. 21, is exerting its maximum tension, the tension of this spring must be sufficient so that while the lever 67 is held in contact with the stop 71, the retaining member 17 will be held closed. After the lever 67 leaves the stop 71 under the influence of the lug 72, the relative positions of these described parts does not change during the further movement thereof thus maintaining the retaining member 17 closed, until such time as the lever 67 is arrested in its movement by the stop 71.
- Of course at all times the arm 68 and lug 72 carried thereby have clearance of the stop 71.
- Mounted to operate beyond the forward end of the sheaf holder 16 is a butter 73 preferably circular in shape as illustrated in Fig. 2. The function performed by this butter is of course to even up as much as possible the butts of the sheaves composing the stock. This butter 73 is held by any suitable frame. We show this frame as composed of a vertical rod 74 and a horizontal bar 75. These members are suitably secured to the said butter. Rods 76 form the side members of the butter frame, and the inner ends of these rods pass through the ends of the horizontal bar 75. Secured to the outside of the horizontal members 2 and 4 are brackets 77 in which have sliding movement the rods 76. The said rods 76 are tied together at their outer ends by suitable angle plates 78 and a tie rod 79. Secured to or formed a part of the axle 14 at each side thereof and below the ends 13 are arms 80, and connecting these arms with the lugs 1 of the butter 73 are connecting rods 81. In order to allow clearance between the ends of the stock and the butter 73 during the inverting movement of the

sheaf holder 16, the means just described is provided. As the axle 14 starts to revolve around its ends 13, the movement given the arms 80, through the medium of the connecting rods 81 will slide the butter 73 and its frame backward the required distance.

The connecting arms 81 are made of two portions connected together as shown at 82 in such a manner as to make them adjustable. 10 83 are a series of supporting rods for the frame of the butter.

The position of the butter 73 may be adjusted on the side rods 76 so as to provide for the length of the sheaves, which of 15 course will depend upon the length of the straw, which sometimes will be long or short. To provide for this adjustment a plurality of holes 84 are formed in the side rods 76, and by means of the split pins 85 the said 20 butter may be held in adjusted position. In order to allow for the adjustment of the butter 73 we have constructed the connecting rods of two parts adjustably connected together as before mentioned.

25 In order to prevent displacement of the sheaves in the sheaf holder 16 during the inverting movement thereof, any suitable means may be provided. For this purpose we prefer to mount in the retaining member 17 and the sheaf holder 16, a plurality of teeth *c* mounted in a backwardly inclined position, that is, with their ends pointing toward the outer end of the sheaf holder. When the sheaf holder is full and occupies 30 the position illustrated in Fig. 19, there will be no possibility of the sheaves being displaced. When the sheaf holder occupies the position illustrated in Fig. 20, the teeth *c* will not interfere with the depositing of the 35 40 stuck on the ground.

In order to allow for the necessary freedom at different times of the movement of the lever 33, we mount on the rod 32 above and below the said lever, coil springs *d*, the 45 inner ends of which rest against said lever. The outer ends of these springs rest against retaining means such as split pins *e*. Of course the hole (not illustrated) formed in the lever 33 through which the rod 32 passes 50 must be of the desired shape to allow for the necessary movement of this rod.

While we have described what we consider to be the best embodiment of our invention, we desire it to be understood that 55 the principle can be embodied in different forms, and we desire not to be limited beyond the requirements of the prior art and the terms of our claims.

What we claim as our invention is:

60 1. An implement of the class described comprising the combination of a suitable frame; a sheaf holder having an open upper side; a retaining member hinged to one side of said sheaf holder and designed to close 65 one portion of said open side when the sheaf

holder is full; means for closing and opening said retaining member; means whereby said sheaf holder is mounted in said frame to be inverted; a reversing cam gear wheel carried by said mounting means for said 70 sheaf holder; a suitable frame; a suitable reversing gear carried by said frame and co-acting with said reversing cam gear wheel to give said sheaf holder the necessary movements, driving means for said reversing 75 gear, means for throwing said reversing gear into and out of operation; a butter positioned beyond one end of said sheaf holder; a frame supporting said butter and slidably held in said suitable frame, and means 80 whereby when said sheaf holder is operated to dump the stuck, said butter will be moved away therefrom longitudinally of the sheaf-holder frame.

2. An implement of the class described 85 comprising the combination of a suitable frame, a frustum-shaped sheaf holder having an open upper side; a retaining member hinged to one side of said sheaf holder at the smaller end thereof and designed to 90 close one portion of said open side when the sheaf holder is full; means for closing and opening said retaining member; means whereby said sheaf holder is mounted in said frame to be inverted; a reversing cam gear 95 wheel carried by said mounting means for said sheaf holder; a suitable frame; a suitable reversing gear carried by said frame and co-acting with said reversing cam gear wheel to give said sheaf holder the necessary 100 movements, driving means for said reversing gear, means for throwing said reversing gear into and out of operation; a butter positioned beyond one end of said sheaf holder; a frame supporting said butter and 105 slidably held in said suitable frame, and means whereby when said sheaf holder is operated to dump the stuck, said butter will be moved away therefrom longitudinally of the sheaf-holder frame.

3. An implement of the class described, comprising the combination of a suitable frame; a frustum-shaped sheaf holder having an open upper side; a retaining member hinged to one side of said sheaf holder, and 115 at the smaller end thereof and designed to close one portion of said open side when the sheaf holder is full; means for closing and opening said retaining member; an axle secured to said sheaf holder, and having its 120 upper ends positioned at an angle thereto and journaled in said frame; a reversing cam gear wheel secured to one end of said axle; a suitable reversing gear co-acting with said reversing cam gear wheel; a suitable frame for said reversing gear; driving means for said reversing gear; means for throwing said reversing gear into and out of operation; a butter positioned beyond 125 one end of said sheaf holder; a frame sup- 130

porting said butter and slidably held in said suitable frame, and means whereby when said sheaf holder is operated to dump the stook, said butter will be moved away therefrom longitudinally of the sheaf-holder frame.

4. The combination with a binder; the deck therefor; the ejecting arms for the sheaves, and means for supporting and operating said arms, of a grain stooker comprising a suitable arm attached to the frame of said binder at one side; a drive wheel mounted in the outer side of said frame; a sheaf holder having an open upper side; a retaining member hinged to one side of said sheaf holder and designed to close one portion of said open side when the sheaf holder is full; means for closing and opening said retaining means; means whereby said sheaf holder is mounted in said frame opposite and below said binder deck; means positioned at one side of said sheaf holder and designed to invert the same and return it to normal position, and receiving its power from the said drive wheel; an arc-shaped table carried by said binder deck and projecting upwardly therebeyond, a sheaf chute hinged to the upper end of said table and designed to extend downwardly at an angle to direct the sheaves into said sheaf holder; a resilient frame carried by the supporting and operating means for said arms, and positioned above said table and provided on its under side with a plurality of catches, and means for moving said sheaf chute upward and holding it in this position during the movement of said sheaf holder so that said sheaf chute will co-act with said frame as a temporary holding means for the sheaves formed during the dumping of the stook.
5. The combination with a binder; the deck therefor; the ejecting arms for the sheaves, and means for supporting and operating said arms, of a stooker comprising a suitable frame attached to the frame of said binder at one side; a drive wheel mounted in the other side of said frame; a frustum-shaped sheaf holder having an open upper side; a retaining member hinged to one side of said sheaf holder, and at the smaller end thereof and designed to close one portion of said open side when the sheaf holder is full; means for closing and opening said retaining member; an axle secured to said sheaf holder, and having its upper ends positioned at an angle thereto and journaled in said frame; means positioned at one side of said sheaf holder and co-acting with said axle and designed to move the same to invert said sheaf holder and return it to normal position, and receiving its power from said drive wheel; an arc-shaped table carried by said binder deck, and projecting upwardly therebeyond; a sheaf chute hinged to the up-

per end of said table and tapering on its inner side toward its front end and designed to extend downwardly at an angle to direct the sheaves into said sheaf holder; an arc-shaped segmental member secured to one end of said axle underneath said sheaf chute and designed to hold said sheaf chute closed when said sheaf holder is being emptied, and means co-acting with said sheaf chute to form a temporary holding means for the sheaves formed during the dumping of the stook.

6. An implement of the class described, comprising the combination of a suitable frame; a sheaf holder having an open upper side; a retaining member hinged to one side of said sheaf holder one end thereof for the purpose of closing one portion of said open side when the sheaf holder is full; an axle secured to said sheaf holder and having its upper ends positioned at an angle thereto and journaled in said frame; means for opening and closing said retaining member comprising a spring arm attached at its upper end to said retaining member and mounted at its lower end on the pintle hinging said member to said sheaf holder; a lever also mounted on said pintle; a lever loosely mounted on the end of said axle adjacent the hinged connection of said retaining member; an arm keyed to said end of said axle; a spring coupling said arm with said second-mentioned lever; an arm coupling said first-mentioned lever with said second-mentioned lever; a lug carried by said first-mentioned arm, a stop carried by said frame against which said second-mentioned lever is normally held by said spring; a drive wheel mounted on an axle at one side of said frame, and means positioned at one side of said sheaf holder and designed to invert the same and return it to normal position and receiving its power from the axle on said drive wheel.

7. In an implement of the class described, the combination with a suitable frame; a sheaf holder having an open upper side; a retaining member hinged to one side of said sheaf holder, and at one end thereof and designed to close one portion of said open side when the sheaf holder is full; means for closing and opening said retaining member, and an axle secured to said sheaf holder, and having its upper ends positioned at an angle thereto and journaled in said frame, of a reversing wheel keyed to the one end of said axle adjacent the hinged connection for said retaining member, and provided on its outer face with two segmental flanges spaced apart, one of said flanges being longer than the other, and provided on each side with a cam face; a circular toothed member secured to said reversing wheel and positioned within said flanges, and spaced apart therefrom; a yielding switch secured to the inner side

of said shorter flange and designed to project beyond the inner end of one of said openings separating said flanges; a suitable frame carried by the first-mentioned frame; 5 a shaft suitably journaled in said second-mentioned frame and provided with a pair of beveled gear wheels loosely mounted thereon and constantly in mesh with said toothed member; a clutch feathered on said shaft; means whereby said clutch is operated to clutch either of said beveled gear wheels to said shaft; a drive wheel mounted on an axle to one side of said first-mentioned frame; a train of gearing interposed between said axle and said shaft for operating the same; a lever hinged to said second-mentioned frame and provided at its inner end with a roller designed to alternately track on the said inner and outer cam faces, 10 and means whereby said clutch and said lever are operated, for the purpose specified.

8. The combination with a binder; the deck therefor; the operating arms for removing the sheaf; supporting means for said arms; a sheaf holder positioned at one side of binder and below the deck thereof; means for supporting said sheaf holder, and means for inverting the same in order to empty it, of an arc-shaped table secured to said deck and projecting above and beyond the same; a sheaf chute hinged at the upper end of said table and normally extending at an outward-downward angle to direct the sheaves into said sheaf holder, a yielding 15 frame, supported by the supporting means for said arms, positioned above said table, and provided in its under side with catches, and means supported by the frame of said sheaf holder and designed to move said sheaf chute and hold it out of the path of movement of said sheaf holder when the same is being emptied, and in order that said sheaf chute may co-act with said frame to provide means to temporarily hold the 20 sheaves formed during the emptying of the sheaf holder.

9. In a grain stooker, the combination of a sheaf holder provided with an open side; a suitable frame which extends beyond one end of said holder; an axle journaled in said frame and secured to said sheaf holder substantially midway the length thereof; means for moving said sheaf holder in order to dump it; a retaining member hinged to one side of said sheaf holder near one end thereof; means for closing said retaining member and holding it closed during the dumping of said sheaf holder; a vertically disposed butter; a frame mounted to move longitudinally on said first-mentioned frame where it extends beyond said holder and providing a support for said butter, and means connected with the axle of said sheaf holder and the frame supporting said butter where- 25 by as said sheaf holder is being inverted

said butter is moved forward longitudinally of said first mentioned frame out of the path of movement of the contents of said holder.

10. The combination with a suitable frame, 70 a sheaf holder provided with an open side; an axle attached to said sheaf holder in two portions one at each side thereof whereby the same is rotatably mounted in said frame; means for moving said sheaf holder in order to dump it; a retaining member hinged to one side of said sheaf holder near one end thereof, and means for closing said retaining member and holding it closed during the dumping of said sheaf holder, of a butter 75 positioned beyond the forward end of said sheaf holder; a suitable frame in which said butter is movably mounted, said second-mentioned frame being supported by said first-mentioned frame; an arm carried by 80 each portion of the said axle at each side of said sheaf holder, and connecting rods connecting said arms with said butter so as to operate said butter, for the purpose specified. 85

11. The combination with a suitable frame; a sheaf holder provided with an open side; an axle attached to said sheaf holder in two portions one at each side thereof whereby the same is rotatably mounted in said frame; means for moving said sheaf holder in order to dump it; a retaining member hinged to one side of said sheaf holder near one end thereof, and means for closing said retaining member and holding it closed during the 90 dumping of said sheaf holder, of a butter positioned beyond the forward end of said sheaf holder; a suitable frame in which said butter is adjustably held and movably mounted, said second mentioned frame being 95 supported by said first-mentioned frame; an arm carried by each portion of the said axle at each side of said sheaf holder, and adjustable connecting rods connecting said arms with said butter so as to operate said 100 butter, for the purpose specified. 105

12. In a grain stooker, the combination with a sheaf holder having an open side; a suitable frame; a drive wheel mounted in said frame; an axle for said drive wheel; an axle secured to said sheaf holder and mounted in said frame; a rotary member carried by one end of said axle at one side of said sheaf holder; reversing means carried by said frame and co-acting with said rotary member to move said sheaf holder to dump the stock and to return it to normal position, and a train of gearing interposed between said axle and said reversing means to supply the operating power, of a retaining 115 member hinged at one side of said sheaf holder and to the upper edge thereof and at one end of said sheaf holder, by means of a pintle; a spring rod keyed to said pintle, and having its outer end secured to said re- 120 125 130

tain ing member; a lever keyed to said pinte; a lever loosely mounted on the end of said axle adjacent said pinte; a link arm connecting said first-mentioned lever with said second-mentioned lever; an arm keyed to said axle and connected by a spring with said second-mentioned lever, a stop carried by said frame against which said second-mentioned lever is normally held by said 10 spring, and a lug carried by said arm, the described parts co-acting to close said retaining member and hold it closed during the dumping of said sheaf holder, and to open said retaining member when said sheaf 15 holder is being returned to normal position.

13. A reversing gear comprising the combination of a reversible shaft; means in which said shaft is journaled; a reversing member keyed to one end of said shaft, and 20 provided on its outer face with two segmental flanges spaced apart, one of said flanges being longer than the other, and provided on each side with a cam face; a circular toothed member secured to said reversing member and positioned within said 25 flanges and spaced apart therefrom; a yielding switch secured to the inner side of

said shorter flange and designed to project beyond the inner end of one of said openings separating said flanges; a shaft suitably journaled in said frame and at right angles to said first-mentioned shaft; a pair of beveled gear wheels loosely mounted on said second-mentioned shaft and spaced apart and constantly in mesh with said 30 toothed member; a clutch feathered on said shaft; means whereby said clutch is operated to alternately clutch said beveled gear wheels to said second-mentioned shaft; a lever pivoted to said frame and provided 35 at its inner end with a roller designed to alternately track on the said inner and outer cam faces; means whereby said clutch and said lever are connected together and operated, and means for driving said second- 40 mentioned shaft.

In testimony whereof we have affixed our signatures in presence of two witnesses.

ASMUNDUR LOPTSON.
GEORGE HENRY RICHARDSON.
